K. K. Solberg + mark.
(written by his son) C. K. Solberg

UNITED STATES PATENT OFFICE.

KNUDT K. SOLBERG, OF CLARKFIELD, MINNESOTA; AASIL SOLBERG ADMINISTRATRIX OF SAID KNUDT K. SOLBERG, DECEASED.

FOUR-HORSE EVENER.

SPECIFICATION forming part of Letters Patent No. 437,730, dated October 7, 1890.

Application filed August 19, 1889. Serial No. 321,439. (No model.)

To all whom it may concern:

Be it known that I, KNUDT K. SOLBERG, who have declared my intention to become a citizen of the United States of America, 5 and who formerly was a subject of the King of Norway and Sweden, now residing at Clarkfield, in the town of Friendship, in the county of Yellow Medicine, State of Minnesota, have invented a new and useful Evener 10 for Two Spans of Horses Abreast, of which the following is a specification.

My invention relates to devices for attaching power to machinery and vehicles which are to be propelled over the ground, and has 15 for its object the provision of a simple and effective device of this character, generally known as a "four-horse power."

The following detailed description will fully indicate the nature, construction, and purpose of my said invention.

The accompanying drawing illustrates my said invention, the figure being a perspective view of the evener arranged upon a tongue.

Similar letters of reference indicate corresponding parts.

A is the tongue of the machine or vehicle to be drawn, and a is a tongue-block screwed or formed upon the rear end of the tongue.

B is the main evener, which is bolted upon 30 the tongue in front of the block, the long arm extending to the right of the tongue and being provided with a hammer-strap b.

Upon the tongue-block is bolted a second evener C, whose long arm extends to the left 35 and is provided with a series of openings c c.

Bars B' B' connect the short end of the evener C to the mid-length of the long arm of evener B, as shown, and B² B² and B³ connect the short arm of the main evener B to the long 40 arm of the evener C, the bars B² B² being adjustable in the holes c c in the inner arm C. Bars B² B² are bolted or pivoted to bar B³ at b², about mid-distance between the main and secondary eveners. At the joint b² affords 45 means for attaching a draw-bar D, having the end next to the joint curved, as shown, which throws the body of the draw-bar over the tongue. The draw-bar rests over the evener B and is provided with a hammer-strap d, to

50 which a double or single tree is secured. A

strap or bar E connects the pivot or bolt of evener C to the pivot or bolt of evener B, and a clip p' confines the draw-bar between it and evener B and strap E. An anti-friction roller may be provided at this point for the draw- 55 bar to work upon.

One horse will be hitched to the left of the tongue and three to the right, all abreast. Two horses will pull upon hammer-strap d and two upon hammer-strap b; but this arrangement may be varied at pleasure.

By the arrangement of eveners and connections shown and the properadjustment of bars B² B² upon the evener C the machine or vehicle can be drawn with precision in a right 65 line, completely equalizing the draft.

Having thus described my invention, what I claim, and desire to secure by Letters Patent, is—

1. In a device of the kind described, the 70 combination of the eveners set with their long arms in opposite directions over the tongue, and having a hammer-strap on the long arm of the main evener and a draw-bar connected to the long arm of the second 75 evener, and curved to present its hammer-strap above the tongue, as set forth.

2. The combination of the eveners B and C, bars B' B', connecting the short arm of evener C to the long arm of evener B, jointed bars 80 B², B², and B³, connecting arm of evener C to short arm of evener B, and the draw-bar D, bolted to the joint of bars B², B², and B³, said draw-bar having a curved portion and a body 85 with a hammer-strap extending over the tongue, as set forth.

3. The combination of the evener B C, bolted to the tongue, a bar or strap E, connecting their bolts, jointed bars B² B³, connecting one end of the eveners, a curved draw- 90 bar attached to the joint of said bars and extending out over the tongue, a clip d', placed over the draw-bar on evener B, and bars B' B', connecting the other end of the eveners, as set forth.

KNUDT K. SOLBERG.
